United States Patent Office

Des. 178,025
Patented June 12, 1956

178,025

SLIPPER

Lawrence M. Thurlow, Portland, Oreg.

Application January 30, 1953, Serial No. 23,350

Term of patent 14 years

(Cl. D7—7)

Fig. 1

Fig. 2

Fig. 3

Fig. 4

In the drawing,

Fig. 1 is a plan view of the slipper;
Fig. 2 is a side elevation of the slipper;
Fig. 3 is a bottom view of the slipper;
Fig. 4 is a front elevation of the slipper; and
Fig. 5 is a rear elevation of the slipper.

I claim:

The ornamental design for a slipper, as shown.
